CLAIM

The ornamental design for a modular adjustable tool shelving and container system, as shown and described.

DESCRIPTION

FIG. 1 is a perspective view of the claimed invention.

FIG. 2 is a front view of the claimed invention.

FIG. 3 is a first side view of the claimed invention.

FIG. 4 is a second side view of the claimed invention.

FIG. 5 is a back view of the claimed invention.

FIG. 6 is a top view of the claimed invention; and,

FIG. 7 is a bottom view of the claimed invention.

The broken-line disclosure in FIG. 1 is for illustrative purposes only and forms no part of the claimed design.
